(57) **CLAIM**

The ornamental design for a ceiling grid tee with uniform effective thickness, as shown and described.

DESCRIPTION

FIG. 1 is a fragmentary perspective view of the ceiling grid tee with uniform effective thickness showing my new design;

FIG. 2 is a left side view of same; A right side view of same is omitted since it is a mirror image of the left side view shown in FIG. 2;

FIG. 3 is a front view of same; A back view of same is omitted since it is a mirror image of the front view shown in FIG. 3;

FIG. 4 is a top view of same;

FIG. 5 is a cross section view of same along line 5—5 of FIG. 2 looking downward; and,

FIG. 6 is a bottom view of same.
